(57) **CLAIM**

The ornamental design for a front shell for an aircraft as shown and described.

DESCRIPTION

FIG. 1 is a front, right-side, and top perspective view of a front shell for an aircraft showing our new design; FIG. 2 is a front, right-side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, shown in a broken line environment of use.

The broken lines depicting the environment of use for the front shell for an aircraft in FIG. 9 form no part of the claimed design.
